FREQUENCY SELECTOR

Warren S. Eaton, Los Angeles, Calif.

Application September 8, 1947, Serial No. 772,607

8 Claims. (Cl. 181—0.5)

1

This invention relates to frequency selection or rate of vibration selection from a medium such as a body of fluid or air, which medium contains a plurality of vibrations of different rates or frequencies, and has for one of its objects to provide for separating from said body of fluid the frequencies contained therein according to their respective rates of vibration in the fluid, and then selectively conveying on one or more of such separated frequencies for use or consideration.

In the present patent application the word "frequency" and the word "vibration" are used to mean substantially the same thing. In other words, a "frequency" is a rate of vibration or a vibration of a predetermined rate. "Frequencies" mean a plurality of different rates of vibration or vibrations of different rates.

Another object is to provide for separating a plurality of frequencies into component frequencies and selectively passing any one or more of such components for use or consideration.

It is also an object of the invention to provide for separating a plurality of frequencies into components, then selecting any one component, and then spreading said selection at either or opposite sides of said selected component and passing such selected components for use or consideration.

It is also proposed to utilize or incorporate the present invention in a stethoscope whereby frequencies emanating from the body of a person may be received and then separated and selectively passed for observation.

With these and other objects in view, the present invention consists in the combination and arrangement of parts as will be hereinafter more fully described, illustrated in the accompanying drawings and pointed out in the appended claims, it, of course, being understood that changes in the form, proportion, size and minor details may be made, within the scope of the claims, without departing from the spirit or sacrificing any of the advantages of the invention.

In the drawings:

Figure 1 is a longitudinal sectional view of a frequency separator and selector showing one embodiment of the present invention.

Figure 2 is a detail fragmentary sectional plan view showing the registered end portions of the valve sections with the valve openings therein in complete registration.

Figure 3 is a view similar to Figure 2 showing the complete valve turned to bring its port into registration with a plurality of ports of the frequency divider or separator.

2

Figure 4 is a similar view showing one of the valve sections turned to bring its port opening out of complete registration with the port of the other valve section.

Figure 5 is a fragmentary detail cross sectional view taken through a pair of registered ports 54 and 55.

Figure 6 is an enlarged detail fragmentary sectional view of one form of pressure change relief means.

Figure 7 is a fragmentary sectional view of a gauge arrangement for use in adjusting the valve of Figure 1.

Figure 8 is a longitudinal sectional view of another embodiment of the invention.

Figure 9 is a longitudinal sectional view of still another embodiment of the invention.

Figure 10 is a plan view of Figure 9, parts being broken away to show an interior construction.

Figure 11 is a detail cross sectional view on the line 11—11 of Figure 10.

Figure 12 is a detail cross sectional view on the line 12—12 of Figure 10.

Figure 13 is a plan view showing the slots in the valve member of Figures 9 and 10.

Figures 14 and 15 are views similar to Figures 11 and 12 showing the double slot arrangement.

Figure 16 is a plan view illustrating the separator and selector of Figures 9 and 10 incorporated in a stethoscope.

Figure 17 is a detail fragmentary sectional view illustrating a vent arrangement.

Figure 18 is a view similar to Figure 17 showing another embodiment of venting means.

Figure 19 is a detail sectional view of a collapsible stethoscope bell as may be employed with the frequency separator and selector of the present invention.

Figure 20 is a cross sectional view of Figure 19 showing the bell collapsed.

Figure 21 is a fragmentary sectional view of a detail.

Referring at first more particularly to the embodiment of the invention as shown in Figure 1, it will be explained that the device includes a frequency divider or separator 5 in the form of a tapered, truncated or substantially conical hollow body divided by partitions 8 into a plurality of chambers 9, 10, 11, etc. so that the separator consists of a series of fluid filled chambers progressively decreasing in diameter from end to end of the series. Also, the chambers progressively decrease in width from the larger to the smaller end of the series. Thus, the cubical volume of the fluid in the chambers progressively decrease from the larger to the smaller end of the part 5.

and, therefore, it will be understood that the separator includes a succession or series of chambers progressively varying in cubical volume from end to end of the series. Each chamber of the series, known as a resonator, contains a predetermined volume of fluid such as will resonate or mechanically vibrate sympathetically with a predetermined frequency. This frequency is known as the resonating capacity of the particular chamber, i. e., the body of fluid contained therein. Each chamber or resonator will, therefore, selectively receive into its fluid contents through its intake port 52 frequency or rate of vibration which it is designed to receive from the plurality of frequencies contained in the volume of fluid in the parts A, 50 and 51. While it is the volume of fluid in any chamber which resonates rather than the chamber itself, for the purposes of the present disclosure these chambers will be referred to as resonator chambers.

A complex frequency or a plurality of frequencies or rates of vibration to be treated and which are contained in a medium such as a fluid, are introduced by the medium into the respective predetermined resonant volume of fluid in each of the resonator chambers of the separator in any suitable manner, as by means of a frequency receiving or collecting bell A connected by a fluid filled tube 50, of suitable length, and may be rigid or flexible, to the adjacent end of a fluid filled tube 51 extending concentrically through the separator and provided with port openings 52, one for each resonator chamber, whereby frequencies or rates of vibration may be picked up, say from the body of a person, by the bell and passed through the medium of fluid into the tube 50 to the fluid filled tube 51 from which the frequencies or rates of vibration will pass through the ports 52 and into the fluid in the respective resonators in accordance with the capacities thereof whereby the complex frequencies picked up by the bell A are separated into component frequencies in accordance with the predetermined or designed resonating capacities or natural period frequencies of the different resonators composing the separator 5.

Provision is made for selectively taking frequencies from the series of resonator chambers. One way of doing this being shown in Figure 1 wherein there is shown an enlarged view of a fluid filled valve casing 53 suitably secured to the separator 5 longitudinally along one wall thereof, such wall being provided with a series of port openings 54, one for each resonator chamber. That wall of the valve casing 53 which lies against and is secured to the adjacent wall of the separator 5 is provided with a series of port openings 55 registered respectively with the port openings 54 of the several resonator chambers so that frequencies may pass from the resonator chambers into the valve casing. Within the valve casing there is valve mechanism for selectively providing communication between the resonator chambers of the separator and the interior of the valve casing. This means consists of a valve in the form of an open-ended cylindrical piston divided transversely into two piston sections 56 and 57 mounted to slide endwise within the cylindrical valve casing 53 and also to rotate therein and having a working fit with the interior walls of the casing. The inner or adjacent ends of the valve sections abut one another, and these abutting end edges are provided with registered tapered or V-shaped notches or slots 56' and 57' so as to jointly form a triangular valve port 75

opening through the wall of the valve which port is intended to be registered selectively with the ports 54 and 55 whereby to selectively pass frequencies from the resonator chambers into the interior of the piston sleeve valves 56 and 57 and thence through its open ends into the fluid filled valve casing 53. With the valve members 56 and 57 rigidly connected for simultaneous movement, in a manner as will hereinafter be described, the valve may be moved endwise within the valve chamber to selectively register the port of the valve with the ports 55 of the valve casing, in the manner as will now be described.

As illustrated in Figures 1, 2 and 3 of the drawings, the piston sleeve valve sections 56 and 57 are abutted in such a relation that the tapered notches or slots 56' and 57' register and form an isosceles triangle with the base of the triangle extending in the longitudinal axial direction of the valve, the other two sides of the triangle extending obliquely across the valve. In Figure 2, the apex portion of the triangular opening is registered with one of the series of ports 55 in the fluid filled valve casing 53, shown in dotted lines in Figures 2 and 3, so that in this position frequencies may pass from one of the resonators of the separator through the aligned ports 54 and 55 and through the apex portion of the port opening in the valve and into the fluid filled interior of the latter and thence into the fluid filled valve casing 53 from which it may be conducted as will be hereinafter described. By sliding the valve endwise, the apex portion of the triangular valve opening may be selectively moved into registration with any of the series of combined ports 54 and 55 for taking frequencies from any one of the separator resonators as will be understood.

With the apex portion of the valve port in registration with any intermediate port of the separator, as in Figure 2, by rotating the complete valve on its longitudinal axis, to the right, in Figure 3, the tapered valve port will come into registration with the next adjacent ports of the separator at opposite sides of the port with which the apex portion of the valve port was first in registration, thereby opening communication from the separator resonators at opposite sides of and next to the original resonator, whereby there will be a spreading of the band of frequencies received from the separator and passed on by the valve to a point of use or consideration. By rotating only one of the valve sections, say 57, as in Figure 4, from the original position as in Figure 2, band spreading may be accomplished at one side only of the frequency received in Figure 2, the original setting of the valve members. Thus, by moving the valve longitudinally and also rotatively, and by separately rotating the valve sections, many valve adjustments and consequent frequency selections may be made.

As illustrated in Figure 1 of the drawings, the valve section 56 is open at one end and is provided at its opposite end with a head 58 which may have openings therethrough or be in the nature of a cross head or other shape so that the right hand end of the valve section may not be entirely closed but will be open enough for the passage of frequencies therethrough. A valve stem 59 is suitably secured to the center of the head 58 and extends at right angles therefrom through and beyond the right hand end of the valve casing 53 where it is provided with a suitable knob or handle 60. The valve section 57 is open at its inner end and is provided at its outer end with a head 61.

similar to the head 58. A tubular valve stem 62, embracing the valve stem 59, is secured to the head 61 and extends therefrom to the exterior of the valve casing where it is provided with a knob or handle 63 lying in close proximity to or in contact with the inner face of the handle 60. By taking hold of both handles 60 and 63, the complete valve may be moved longitudinally in opposite directions within valve casing 53. Likewise, the complete valve may be rotated within the valve casing. By manipulating either handle, its valve section may be rotated independently of the other valve section. Thus, the various adjustments of the valve and its valve sections may be accomplished, as hereinbefore set forth.

One end of the valve casing 53 may be closed in any suitable manner. The outer end of the valve casing may be closed as by means of a screw cap 64 having a central opening for the passage of the valve stems. One or more openings 65 may be provided through the head 64, and the head may be provided with a nipple 66, one for each opening 65, and flexible or other fluid filled tubes, not shown, may be connected to the nipples 66 so as to conduct frequencies to any desired place for use or consideration. It will, of course, be understood that this arrangement, as shown in Figure 1, may be greatly varied and illustrates merely one way of conducting frequencies from the valve casing.

For the purpose of accurately adjusting the valve with respect to the port openings of the frequency separator 5, a gauge has been provided for each of the valve sections, as best illustrated in Figure 7 of the drawings, wherein 53 designates a fragmentary portion of the valve casing, and 56 and 57 indicate the abutted ends of the valve sections. The valve sections are provided with parallel longitudinal gauge lines and transverse gauge lines as indicated. The valve casing is provided with a sealed window 67 for the valve 56 and a sealed window 68 for the valve 57 whereby the gauge lines may be readily viewed. Each window is provided with crossed hair lines 69 with which the gauge markings may be registered and thereby the valve may be accurately set in the well known manner.

While, in Figure 1, means is shown for conducting frequencies from one end only of the valve casing, it will, of course, be understood that suitable provision may be made for conducting frequencies from the opposite end of the casing, if it is desired to do so.

Provision is made for substantially maintaining a predetermined pressure in the medium employed for transmitting the frequencies, usually air, within the device of the present invention. One such means has been shown in detail in Figure 1 of the drawings. The pressure reliever shown is that of a casing 70 suitably secured to the small end of the selector member 5 and surrounding the open adjacent end of the tube or passage 51. The inner end of the part 70 is open, and an elastically yieldable diaphragm 71 is provided within the casing 70, covering the inner open end thereof and extending across the open end of the tube 51. Should pressure build up within the device, it will act against the diaphragm 71 and bulge it out say to the dotted line position thereof, thereby relieving the pressure within the device. A suitable number of vent openings 72 are provided in the casing at the outer side of the diaphragm so as to permit of the necessary movement of the diaphragm. Another form of pressure relieving means is shown in Figure 6 wherein a casing 73

is secured to the smaller end of the separator 5 with its inner end in communication with the open end of the tube 51. Within the casing 73 there is a reciprocating head or piston 74 lying across the open end of the tube 51 and subject to the pressure of a spring 75 against its outer face and the pressure within the device on its opposite face. Suitable vent openings 76 are provided in the casing 73 to facilitate the movement of the piston 74 under a change in pressure within the device.

It will be noted that in each form of pressure reliever, the air or other medium carrying frequencies is not vented to the atmosphere but is retained within the sealed device and so there is no escape or loss of frequencies due to the action of either of the pressure relievers, and extraneous frequencies cannot pass into the device through either of the pressure relievers.

The valve mechanism shown in Figure 1 of the drawings is intended for selecting frequencies and bands of frequencies from the separators 5. However, frequencies may be taken from the resonator chambers of the separator without using the valve, as frequencies may be individually taken from the resonator chambers by means of valved nipples 77 provided upon the peripheral wall of the separator and communicating with the respective resonator chambers. If desired, any one or more of the nipples 77 may be provided, see Figure 21, with means responsive to the frequencies contained in any resonator chamber, such as a casing 78 having one end closed and provided with a tubular connection 79 threaded or otherwise secured to the outer open end of one of the nipples 77. Extending across the open end of the casing is a diaphragm 80 which closes the casing against the escape of frequencies into the atmosphere and prevents passage of extraneous frequencies into the separator. This diaphragm may be associated with any means to be actuated by the vibrations of the diaphragm. A pin 81 carried by the diaphragm at the center thereof may be employed for this purpose in a manner as is well understood. This diaphragm may be constructed to resonate at the frequencies contained in the resonator chamber to which it may be attached.

In Figure 8 of the drawings there has been shown on an enlarged scale a somewhat modified form of the valve mechanism, and in this figure there has been illustrated a fragmentary portion of the separator 5 which is the same as that hereinbefore described. Secured to the outer periphery of the separator is a valve casing 82 similar to the valve casing 53 of Figure 1, and provided with a series of ports 55 registering with the series of ports 54 in the separator as hereinbefore described. Instead of having the valve divided into sections, there is a single fluid filled tubular sleeve valve 83, one end of which projects beyond the valve casing, which latter is provided with a stuffing box 84 through which the outer end of the tubular valve works. The tubular valve is provided with a triangular valve port opening 85 as in Figure 1, having its apex arranged for registration selectively with the ports 55 of the valve casing. The tubular valve member is capable of endwise movement and rotative movement for the purpose as described for Figure 1. The externally projecting end of the tubular valve member may be provided with any suitable means for leading off frequencies, as by being provided with a cap 86 having an open outer end for connection with a micro-

phone indicated at 81. The valve casing 82 is provided with a sealed window 88 to facilitate viewing gauge lines as hereinbefore described and illustrated in Figure 7 of the drawings. Provision may be made for conducting frequencies from either or both ends of the valve casing if it is desired to do so.

Another embodiment of the invention has been shown in Figures 9 to 16, inclusive, wherein a frequency divider and separator 5 in the form of a substantially conical hollow body is mounted concentrically upon a tube 1 so as to be slideable and also rotatable thereon. This frequency separator has opposite end walls 6 and 7, thus defining a closed conical chamber which is subdivided by partitions 8 into a plurality of sections or chambers 9, 10, 11, etc., throughout the length of the separator part 5. As shown in the drawings, the periphery of the separator part 5 may be stepped down from the larger end to the smaller end, and, usually the cylindrical chambers of the part 5 may be progressively decreased in diameter. They also progressively decrease in width from the larger to the smaller end of the part 5 as shown in the drawings. Thus, the cubical fluid volume of the chambers progressively decrease from the larger end to the smaller end of the part 5, and, therefore, the separator includes a succession or series of fluid filled resonator chambers progressively varying in cubical fluid volume from end to end of the series. Each chamber constitutes a resonator intended to receive frequencies corresponding to the resonating capacity or natural period frequency of the volume of fluid in the chamber as such frequencies are passing into the separator. The several resonator chambers are closed at their inner peripheries by a circular wall 12 in the form of a tube passing through the partitions 8 and the end walls 6 and 7.

While the separator 5 has been shown and described as of conical shape, it may be of any shape or form so long as the cubical fluid volume of the respective chambers or resonators thereof are graduated in size or capacity so as to resonate respectively in accordance with the frequencies or rates of vibration of the band of frequencies for which the device is designed.

For making selections with respect to the selector 5, communication between each resonator and the interior of the fluid filled tube 1 is afforded by an opening or port 13, in the inner peripheral wall 12 of the separator, such opening 13 being intended to be registered with slots 14 and 15 provided in the tube 1. As shown in Figures 9, 10 and 13, the slots 14 and 15 extend longitudinally of the tube 1 and are tapered longitudinally. The narrow ends of the slots are adjacent one another and are spaced from one another at 16 so that at this point the tube 1 is continuous throughout its periphery and constitutes a valve for selective registration with the port openings 13 in the inner peripheries of the resonators by relative sliding movements of the separator 5 and the tube 1. Such valve portion is shown, in Figures 9 and 10, as closing the port 13 of the largest resonator 9, whereby frequencies corresponding to the other chambers may pass through the open ports 13 of said other resonators and thus be absorbed and filtered out, with the result that the frequency corresponding to the resonator 9 will be the frequency which is permitted to pass through the fluid filled tube 1 for use or consideration. By reference to Figures 10 and 13 of the drawings, it will be

seen that corresponding edges 17 of the slots are in alignment and extend longitudinally of the tube, whereas the other longitudinal edges 18 of the slots incline away from the edges 17 and also from the valve part 16 towards the outer ends of the slots, thus producing triangular or longitudinally tapered slots. In the position of the separator 5, as shown in Figure 10, it will be seen that the ports 13 in the inner peripheral wall thereof are in longitudinal alignment with one another and also in alignment with the slot 14 and are disposed adjacent the wall 17 of the slot which extends longitudinally of the tube 1, with the exception of the port of the larger resonator 9, which port is closed by the valve part or member 16. By moving the separator 5 longitudinally to the right or the tube to the left, the port 13 of the next smaller resonator 10 may be brought into registration with the valve part 16 of the tube whereby the port of the resonator 9 will be in registration with the slot 15, and all of the other ports 13 in registration with the slot 14, whereby the only frequency which will be passed through the tube will be the frequency corresponding to that of the resonator 10 which has been cut off by the valve 16 from communication with the fluid in the interior of the tube 1. It will thus be understood that by selectively and relatively moving the parts 1 and 5, the port 13 of any predetermined resonator may be brought into registration with the valve 16 to cut off communication between the fluid in the interior of the tube 1 and the fluid in the interior of the resonator having the resonating capacity or natural period frequency of the frequency which is to be passed on for use or consideration.

By adjustably rotating either the tube 1 or the separator part 5 so as to move the ports 13 towards the inclined edge 18 of the slot, such ports may be closed successively or selectively without requiring relative longitudinal movement of said parts. By relatively rotating the parts 1 and 5 in the opposite direction, so as to move the ports 13 towards the longitudinal edge 17 of the slot in the tube 1, all of the ports may be simultaneously closed, and then there will be no modification or further selectivity of frequencies which are introduced into the tube 1 and passed on for any purpose.

It will, therefore, be understood that by relatively moving the parts 1 and 5, any selected port 13 may be closed by the valve 16 while the other ports are in registration with one of the slots 14 and 15, and by relative rotation of said parts, a plurality of selected ports 13 may be closed while permitting the other ports to remain in communication with one or the other of the slots. Normally the separator 5 is yieldably held at one of its limits on the tube by a spring 19 with one end bearing against the larger end of the separator 5 and its opposite end bearing against a suitable stop 24 provided on the tube 1. Preferably, the tubular inner wall 12 of the separator is projected or extended at opposite ends of the separator as at 20 and 21, the outer ends of said parts 20 and 21 being provided respectively with stuffing boxes 22 and 23 so as to close the ends of the composite fluid filled tube 20, 12, and 21 and thereby prevent the entrance of extraneous frequencies or rates of vibration into said tube. Furthermore, a suitable stop 24' is provided upon the tube 1, preferably in the form of an annular flange or collar for contact by that end of the tube which projects

at the smaller end of the separator to limit the endwise movement of the separator 5 under the influence of the spring 19. The stops 24 and 24' may be in the form of nuts threaded on tube 1 for adjustment thereon.

Normally, the stuffing boxes 22 and 23 are adjusted to permit smooth sliding and turning movements of the parts 5 and 1 while at the same time excluding extraneous frequencies.

When the separator 5 has been moved to any selected position on the tube 1, it may be held or locked in such position by tightening one of the stuffing boxes 22 or 23 so as to compress the packing and thus lock said stuffing box and the separator 5 on the tube 1 in such selected position.

The stuffing boxes 22 and 23 prevent leakage under normal conditions; permit leakage or venting under pressure changes; and constitute locking means or units for holding or locking the separator 5 in any adjusted position on the tube 1.

In the adjusted position of the valve part 16 in Figures 9 and 10, the received frequencies are separated into components by the respective resonators of the separator 5, while the valve 16 makes the selection of the frequency to be used or considered in that such valve 16 closes the port 13 of the resonator 9, and so the frequency which would otherwise pass into resonator 9 is passed on through tube 1 to a place of use and thus separated from the others. In other words, the separator part 5 together with either of the slots 14 and 15, and the valve 16, constitute means for separating the received frequencies into components in that some of the components are separated out by means of the resonators and others are separated by the valve from those separated out by the resonators. That part of the tube 1 which has the slots 14 and 15 and the valve 16 constitutes means for selecting the separated frequency or frequencies to be passed on for use. Accordingly, it will be understood that Figures 9 and 10, like Figures 1 and 8, present frequency separating means and means for selecting the separated frequency to be passed for use.

In the embodiment of my invention in a stethoscope, as shown in Figure 16, and with the use of a collapsible bell, as illustrated in Figures 19 and 20 and described in detail in my copending patent application, by placing the bell against the body of a person and pressing against the small end of the separator 5, the bell may be selectively collapsed thereby reducing the effective cubical volume of the fluid in the bell and also the area of the mouth of the bell, thereby obtaining a relatively coarse frequency selection which will be conducted by fluid through the tube 1 into the separator 5. In the separator the frequencies selected by the bell will be more finely separated, and through the use of the valve part 16 any frequency may be selected. Thus, a relatively coarse selection may be made by selectively collapsing the bell, such selection may be separated into its component parts by the separator 5, and the valve 16 used to make any desired selection from the finely separated frequencies, and such selection conducted by fluid through tube 1.

By proportioning the spring 19 and the resonators in separator 5 with respect to the collapsibility of the bell, and when the separator 5 is moved against the spring so as to progressively collapse the bell against the body of a person, the travel of the separator along the tube 1 will

be in a predetermined relation to the collapsing of the bell and consequently the separator will be automatically positioned on the tube 1 so as to properly separate the fluid borne frequencies conducted thereto by the bell in its progressively collapsed condition, and the valve part 16 will thus be located to close the resonator corresponding to the desired or selected frequency, and thus said frequency will be conducted through fluid in tube 1.

By employing a gauge such as is shown in Figure 7, and indicated at 70 in Figure 16 any predetermined frequency selection may be made by sliding the separator 5 along the tube until the desired marking on the gauge 70 appears through the window thereof.

The separator 5 may be first set on the tube 1 to the position necessary for locating the valve 16 to close the ports 13 of any predetermined resonator of the separator, and then the separator may be locked in this set position by tightening either or both of the stuffing boxes 22 or 23. Then the resonant frequency of the closed resonator will be prevented from entering into said resonator but will be conducted on through the fluid in tube 1, while the other frequencies will pass into and be trapped in their respective resonators of the separator.

As distinguished from the use of a rigid bell, when a collapsible bell is used, the collapsing thereof will make a preliminary selection of frequencies, causing a lower intensity of undesirable frequencies to be fluid borne to the separator than when the full size bell is employed, thereby enhancing the efficient operation of the separator and selecting of the desired frequency.

The collapsible bell of my invention may be made of any elastically yieldable material such as will permit collapsing of the bell for the purposes of the invention. I contemplate specifically the use of rubber, sponge rubber, any of the synthetic rubber materials, such as neoprene or any other elastic material suitable for the purpose.

Pressure changes may occur in the use of the present instrument and provision has been made to relieve such pressure changes.

To maintain a constant pressure within the device when in use, as shown in Figure 17, there may be provided in one wall of the tube 1 a vent opening 29 leading to a vent nipple 30, the inner end of which communicates with the vent opening 29. A screw cap 31 is provided upon the outer open end of the nipple 30 and is provided with an exhaust vent opening 32. A valve member 33, preferably in the form of a ball, is contained within the inner portion of the nipple 30 and is normally held against the vent opening 29 to close the same by means of a coil spring 34 bearing at one end against the valve and at the other end against the cap 31. Under normal conditions and handling of the device, the valve 33 is held closed, but should the source of frequencies cause an increase of pressure within the device, the valve 33 will open and thus vent the increase of pressure through the opening 32 to the atmosphere. This is an automatic operation.

In another portion of the tube there is provided an inlet opening 35 communicating with a nipple 36 carried by the tube 1 and provided at its outer end with a screw cap 37 having an inlet opening 38 in its outer end, which opening is normally closed by means of the valve 39 subject to the pressure of the spring 40 so

that when pressure is lowered within the device 1, atmospheric pressure will open the valve 39 and admit air through the opening or port 35 into the device. This is an automatic operation.

To provide for relieving pressure changes by a manual operation, the arrangement shown in Figure 18 is provided. A pressure relief port 41 is provided in the tube 1, and associated therewith is a nipple 42 provided at its outer end with a screw cap 43 having a vent opening 44 normally closed by a valve 45 within the cap 44 and having a stem 46 passing through the vent opening and provided at its outer end with a head or button 47, there being a helical spring 48 surrounding the stem and bearing in opposite directions against the inner face of the head 47 and the outer end of the cap. In this arrangement the spring maintains the valve closed. The operator by pressing upon the head 47 and compressing the spring, may open the valve 45 whenever desired.

What I claim is:

1. A frequency selector for selecting frequencies from a volume of fluid containing a plurality of vibrations of different frequencies comprising a frequency separator made up of a plurality of fluid filled resonator chambers of different cubical volumes and resonator capacities, a fluid filled valve casing having ports communicating with the respective chambers, a tubular open ended valve working within the casing and provided with a triangular valve port for selective registration with the ports of the valve casing, said valve being rotatable to bring its port into registration with a plurality of the ports of the valve casing.

2. A frequency selector for selecting frequencies from a volume of fluid containing a plurality of vibrations of different frequencies comprising a frequency separator made up of a series of fluid filled resonator chambers of different cubical volumes, a valve casing having ports communicating with the respective chambers, a reciprocator tubular open ended valve working in the casing and divided into two tubular sections provided in their inner ends with tapered openings which when registered provide a triangular valve port for selective registration with the ports of the valve casing, said valve being adjustable endwise within the casing, and said valve sections being independently rotatable within the valve casing.

3. A frequency selector for selecting frequencies from a volume of fluid containing a plurality of vibrations of different frequencies comprising a frequency separator made up of a plurality of fluid filled resonator chambers of different cubical volumes and resonating capacities, a fluid filled valve casing extending concentrically through the resonator chambers and having ports communicating with the respective chambers, a tubular open ended valve working within the casing and provided with a triangular valve port for selective registration with the ports of the valve casing, said valve and casing being relatively rotatable to bring the triangular port into registration with a plurality of the ports of the valve casing.

4. A frequency selector for selecting frequencies from a volume of fluid containing a plurality of vibrations of different frequencies comprising a frequency separator made up of a plurality of fluid filled resonating chambers of different cubi-

cal volumes and resonator capacities, a fluid filled valve casing extending concentrically through the chambers and having ports communicating with the respective chambers, a tubular open ended valve movable longitudinally and rotatably within the casing and provided with a pair of longitudinally aligned triangular valve ports for selective registration with the ports of the valve casing, the inner ends of the triangular valve ports being spaced to provide a valve element in the valve member.

5. A frequency selector for selecting frequencies from a volume of fluid containing a plurality of vibrations of different frequencies comprising a frequency separator made up of a plurality of fluid filled resonator chambers of different predetermined cubical volumes and resonating capacities, a valve casing extending concentrically through the chambers and having ports communicating with the respective chambers, a tubular open ended valve movable longitudinally and rotatably within the casing and provided with a triangular port for selective registration with the ports of the valve casing, a frequency pick-up device for receiving a plurality of mechanical vibrations of different frequencies and adjustable for frequency selectivity and connected to one end of the valve member, and ear pieces connected to the other end of the valve member.

6. The herein described method of treating sound vibrations of different frequencies, comprising the steps of receiving in a confined body of air a plurality of vibrations from a vibrating member, excluding other vibrations from said confined body of air, separating said confined vibrations into component vibrations, selecting from said separated components and maintaining a predetermined pressure in the confined body of air.

7. The herein described method of treating air sound vibrations of different frequencies received from a vibrating member, comprising receiving said vibrations in a confined body of air, excluding other vibrations from the confined body of air, individually trapping components of said vibrations while confined, selecting from the trapped vibrations, conducting said vibrations to a point of use, and maintaining a predetermined pressure in the confined body of air.

8. The herein described method of treating vibrations of different frequencies, comprising the steps of receiving in a body of confined air a plurality of such vibrations, individually receiving from the said body of air and trapping vibrations, selecting a predetermined trapped vibration, conducting said selected vibration to a point of use, and maintaining a predetermined pressure in said body of confined air.
